UNITED STATES PATENT OFFICE.

FRANK J. BENNETT, OF CAMBRIDGE, OHIO.

AUXILIARY SHIELD FOR AUTOMOBILES.

1,410,987.

Specification of Letters Patent. Patented Mar. 28, 1922.

Application filed February 14, 1921. Serial No. 444,657.

To all whom it may concern:

Be it known that I, FRANK J. BENNETT, a citizen of the United States, residing at Cambridge, in the county of Guernsey and State of Ohio, have invented certain new and useful Improvements in Auxiliary Shields for Automobiles, of which the following is a specification.

My invention relates to an auxiliary shield for automobiles, for protection against the sun and weather.

An important object of the invention is to provide a shield of the above mentioned character, having means whereby it may be adjustably attached directly to the front bow of the automobile top, without disturbing the connections between the usual wind shield frame post and the top.

A further object of the invention is to provide means to properly hold the auxiliary shield in adjusted position.

Other objects and advantages will be apparent during the course of the following description.

25 In the accompanying drawings forming a part of this specification, and in which like numerals are employed to designate like parts throughout the same,

Figure 1 is a perspective view of an auxiliary wind shield embodying my invention, showing the same in use,

Figure 2 is a side elevation of the same, parts in section,

Figure 3 is a fragmentary perspective view of the auxiliary shield,

Figure 4 is a plan view of the auxiliary shield,

Figure 5 is a detail section taken on line 5-5 of Fig. 2,

40 Figure 6 is a side elevation of the auxiliary wind shield, showing the same applied to the wind shield of the Ford automobile,

Figure 7 is a perspective view of a bracket used in connection with the Ford automobile,

45 Figure 8 is a side elevation of the auxiliary shield, showing the same applied to a closed car, and,

Figure 9 is a perspective view of a bracket used in connection with the closed car.

50 In the drawings wherein for the purpose of illustration are shown preferred embodiments of my invention, the numeral 10 designates the frame of the auxiliary shield, which frame is preferably rectangular, and may be formed of metal or other suitable material. The frame is provided at its ends

with trunnions or extensions 11, preferably formed integral therewith, and screw threaded, as shown. The frame 10 is covered with material 12, which may be top material, 60 artificial leather, or any other suitable material.

The numeral 13 designates preferably flat hinge leaves, provided at their forward ends with eyes 14, which are formed or bent 65 thereon, and pivotally receive the rear side of the frame 10. Particular attention is called to the fact that these hinge leaves are spaced inwardly for a substantial distance from the ends of the frame 10, for a purpose 70 to be more fully explained.

The numeral 14 designates L-shaped attaching brackets, Figures 2 and 4. These attaching brackets are adapted to be secured to the inner longitudinal side of the front 75 bow 15 of the top 16, at points spaced inwardly from the ends of the front bow. Screws 17 or the like serve to hold these L-shaped brackets to the bow 15. Each hinge leaf is secured to the horizontal portion of the bracket 14 by two bolts 18 or the like, for forming a rigid connection.

The numeral 19 designates adjustable supports for the auxiliary shield, each comprising upper and lower links 20 and 21. The 85 upper link 20 is apertured at its upper end, to pivotally receive the trunnion 11 carrying a nut 21'. The upper link 20 also has a longitudinal slot 22 near its lower end, receiving a bolt 23, carried by the lower link 90 21. The bolt 23 carries a thumb nut 24, whereby links 20 and 21 may be clamped together. The lower end of the link 21, Figure 5, fits between the ends 25 of a strap 26, and is connected therewith by a bolt 27, such bolt 95 serving to suitably retain these parts together and to also suitably clamp the strap to the post 28 of the wind shield 29. The strap 26 is located between the pivots of the wind shield sections. At this point it is pointed 100 out that by arranging the hinge leaves 13 and brackets 14 inwardly of the ends of the front bow 15 and inwardly of the wind shield posts 28, the connections between the wind shield posts and the front bow 15, ordinarily 105 occurring at the top of the wind shield posts, are in no way disturbed, thus enabling the auxiliary wind shield to be quickly and conveniently placed in position and removed when desired. Further, by employing 110 L-shaped brackets 14, access may be more readily had to the screws 17, from the in-

terior of the machine, as it would be difficult to operate screws passing vertically through the leaves 13, in advance of the wind shield, as the space between the wind shield and the 5 front edge of the front bow 15 is comparatively small.

In Figure 6, I have shown the auxiliary shield applied to a Ford automobile. The construction of the wind shield and the supports 19 are identical, and the wind shield is attached to the front bow of the top in 10 the same manner. However, the strap 26 is dispensed with, and the lower link 21 is pivoted to a bracket 29, which is secured to 15 the adjusting knuckle or bolt 30 of the upper top section of the wind shield, the bracket being offset inwardly.

In Figures 8 and 9, the auxiliary wind shield has its spring leaves 13 directly mounted upon the under surface of the top 20 31 of a closed automobile top, the L-shaped brackets 14, in this instance being omitted.

The same form of supports 21 are employed, but the lower links 21 are preferably 25 slightly curved longitudinally and are pivoted upon lugs 32, by bolts 33. These lugs are carried by plates 34, attached to the front 30 of the car body.

From the foregoing description it is obvious 35 that with either form of the device, the auxiliary shield may be quickly adjusted, as desired, and locked in adjustment at a selected position. The wind shield may be readily secured in place, in a convenient manner.

It is to be understood that the forms of my invention herewith shown and described are to be taken as preferred examples of the 40 same, and that various changes in the shape, size, and arrangement of parts may be resorted to without departing from the spirit of my invention or the scope of the subjoined claims.

Having thus described my invention, what 45 I claim is:

1. An auxiliary shield comprising a frame having a cover, said cover being provided near the frame with openings which are dis-

posed near the ends of the frame, hinge leaves having eyes extending into said openings and pivotally receiving the rear side of said frame, said hinge leaves being adapted to be arranged beneath the front bow of the automobile top, brackets secured to the hinge leaves and engaging the rear longitudinal edge of the bow, means for securing the brackets to such edge, and adjustable means for holding the auxiliary shield in the desired elevated position.

2. An auxiliary shield of the character described, comprising a frame, a covering for the frame, substantially flat hinge leaves pivotally connected with the rear side of the frame and adapted to be arranged beneath the lower face of the front bow of the automobile top, L-shaped brackets having their horizontal portions secured to the rear ends of the hinge leaves and their vertical portions engaging the rear vertical edges of the bow, substantially horizontal screws connecting the vertical portions of the bow, and adjustable means for holding the auxiliary shield in the desired elevated position.

3. An auxiliary shield adapted to be arranged in advance of the ordinary wind shield of an automobile, comprising a frame, a covering for the frame having openings near the rear side of the frame, said openings being spaced from the ends of the frame, hinge leaves having their forward ends bent into eyes extending through said openings and pivotally receiving said rear side of the frame, said hinge leaves engaging the lower surface of the front bow of the automobile top, L-shaped brackets secured to the rear edge of said front bow and secured to the rear ends of the hinge leaves, trunnions carried by the ends of said frame, pivoted supports connected with the trunnions at their forward ends, straps encircling the posts of the main inner shield and having the rear ends of the supports therebetween, and bolts passing through the said straps and the rear ends of the supports.

In testimony whereof I affix my signature.

FRANK J. BENNETT.
